UNITED STATES PATENT OFFICE.

HORACE B. MURDOCK, OF DETROIT, MICHIGAN, ASSIGNOR TO THE ANDERSON SAFETY ELEVATOR COMPANY, LIMITED, OF SAME PLACE.

ELEVATOR-HATCHWAY COVER.

SPECIFICATION forming part of Letters Patent No. 599,857, dated March 1, 1898.

Application filed February 8, 1896. Renewed February 13, 1897. Serial No. 623,815. (No model.)

To all whom it may concern:

Be it known that I, HORACE B. MURDOCK, a citizen of the United States, residing at Detroit, in the county of Wayne and State of Michigan, have invented certain new and useful Improvements in Elevator-Hatchway Covers, of which the following is a specification, reference being had therein to the accompanying drawings.

10 This invention relates to that class of hatch-covers which are automatically deposited by the elevator-cab to close the openings in the floors after the passage of the cab and wherein one set of covers is carried beneath the cab and will be deposited in the opening as the cab ascends, and another independent set is carried on top of the cab and will be deposited in the opening as the cab descends.

15 The object of my invention is to furnish improved means for operating such hatch-covers and which are in the nature of an attachment adapted to be applied to any style of elevator and work equally well whether the elevator moves fast or slow and without creating noise.

20 To this end my invention consists in the novel construction, arrangement, and operation of carrying-latches which form the means for carrying the hatch-covers of the lower set beneath the cab; further, of supporting-latches located in the hatch-openings, by which the covers are supported thereon, and, further, in certain devices for tripping the carrying-latches, all as more fully hereinafter 25 described, and shown in the drawings.

30 Figure 1 is a diagram section showing an elevator to which my invention is applied. Fig. 2 is a diagram plan thereof. Fig. 3 is a sectional perspective view of the platform of the cab in one of the hatch-openings in the elevator-shaft. Fig. 4 is a vertical cross-section substantially on line $x-x$ in Fig. 2, illustrating the operation of the device. Fig. 5 is an elevation of one of the supporting-latches 35 in the hatch-opening. Fig. 6 is a vertical section thereof on line $y-y$ in Fig. 5. Figs. 7 and 7^a are horizontal sections thereof on line $v-v$ in Fig. 5 and illustrating the device as in supporting a cover of the lower and upper 40 set, respectively. Fig. 8 is a side elevation of one of the supporting-latches, illustrating

the same as in use. Figs. 9, 10, 11, and 12 show the construction of the carrying-latches for supporting the lower set of hatch-covers and representing the same in different elevations and in vertical section, respectively.

45 In the drawings my invention is shown as applied to an ordinary freight-elevator of known construction, in which A represents the cab; A', its platform; B, the hoisting-rope, 60 and C the hatch-opening, through which the cab passes through the floors.

55 D refers to the lower set of hatch-covers, and D' to the upper set. Both sets can be made alike, except that the covers of the upper set must have a central aperture for the hoisting-rope to pass through. These covers may be of any suitable construction that will combine strength with lightness and render them fireproof. Those shown in the drawings 65 consist of light metallic tubular frame-bars a, connected by corner-brackets a' to form rectangular frames adapted to the openings in the floors and filled with asbestos, supported by strong wire-netting, all of known 70 construction and forming no part of my invention. As many of these covers as there are hatch-openings to be covered in the elevator-shaft are provided for each set, those of the upper set being supported one above 75 the other on top of the cab, and those of the lower set are suspended from below the platform of the cab when not in position in the hatch-opening. To this end the cab is provided with four carrying-latches E for each 80 cover, which are secured near the corners of the cab, on opposite sides thereof, and which are adapted to support the covers one below the other. The construction of these carrying-latches is shown in detail in Figs. 9, 10, 85 90 and 12 and is as follows:

95 Within a hanger-frame e, secured at its upper end to the platform A' and extending vertically below thereof, is pivotally secured at e' the hook latch-bar e², provided with a shoulder e³ and a curved guide e⁴ below the same. This hook is normally held in projected position, as shown in Fig. 9, by means of a spring e⁵ and is adapted to be retracted within the frame by a trip-lever e⁶, pivotally secured at 100 e⁷ and having a slotted arm engaging a pin e⁸ in a slot of the hook in which the trip-lever

works, all so arranged that if any downward pressure is brought upon the outwardly-projecting arm of the trip-lever the hook is retracted. The frame *e* of the latch projects below the hook and forms an inclined guide *e*⁹, and over the upper portion of the latch is preferably secured a protecting-shield *e*¹⁰. As there are as many latches at each of the four corners of the cab-platform as there are covers to be supported, I preferably place the latches at each corner side by side and unite the different frames thereof into one common frame, Figs. 9, 10, 11, and 12 of the drawings showing two latches united and with their hook-bars at such relative distance below each other and below the car-platform as to give space for two covers. In the same manner additional covers are supported to the required number. For supporting these covers upon the shoulders *e*³ of the latch-hooks the covers are provided correspondingly therewith with supporting-rollers *d*, secured in any suitable manner to the frame-bars, and to avoid noise in the operation of the device these rollers are preferably of compressed fiber or other noise-deterring medium, and, if desired, the shoulders *e*³ of the latches, upon which these rollers are adapted to engage, may be covered with rubber or leather. In this manner the elevator-cab in its upward journey carries the covers, and each cover is successively released at the proper opening from its carrying-latches in the operation of the device by means of stops *F*, secured to the combing in the hatch-opening and projecting into the path of the trip-levers of the carrying-latches. Thus there will be four of such stops in each hatch-opening, the one in the lowest opening registering with the trip-levers of the lowest cover, the one in the cover next above registering with the trip-levers of the cover next above from the lowest, and so on to the top, each set of stops in the hatch-way being thus out of the way of all the trip-levers of the covers not belonging to it and operating only upon its particular cover. As each hatch-cover in the travel of the cab is thus released from the cab it is immediately held fast in position in the opening by means of the supporting-latches *G*, of which there are four for each cover located in each hatch-opening. The construction and operation of these supporting-latches are shown in Figs. 4, 5, 6, 7, and 8 and will now be more fully described in detail.

Within a suitable housing *g*, which is adapted to secure the supporting-latch in the hatch-openings, is pivotally secured at *g*' a jointed latch-bar composed of two parts *g*² *g*³, connected at or near the middle by a hinge-joint *g*⁴. This latch-bar is retained at its upper end within the housing by means of a pin *g*⁵ passing through a slot *g*⁶ in the upper end of the latch-bar, and it is maintained in the normal position (shown in Fig. 6) by means of a suitable spring *g*⁷. In the face of this latch-bar at the joint is formed a recess *g*⁸, formed

with rounded corners. Above and below this recess the latch-bar is provided with inclined guiding-faces *g*⁹ *g*¹⁰, the former one of which forms the inclined shoulder *g*¹¹.

To make the latch in operation noiseless, a recess is formed at the hinge connection between two overlapping portions of the latch-bars, in which a piece of rubber *g*¹² is secured, which forms the lower shoulder of the recess. The latch being constructed and arranged in this manner, it operates as follows: Each hatch-opening has four of these latches, supported near the corners upon opposite sides and with the recess *g*⁸ of the latch-bar in the proper position to receive the hatch-cover at the very point at which it is released from the cab by the tripping of the carrying-latches. To this end all the covers of the lower set are provided alike near the corner with the rollers *a*², and corresponding therewith a like roller *a*² is also correspondingly placed upon the side of the platform, as shown in Fig. 3. All these rollers *a*² are in vertical line with each other and with the latch-bars of the supporting-latches in the different hatch-openings, and in the operation of the device the hatch-covers are supported by the latches by means of these rollers *a*² entering into the recesses *g*⁸ at the moment the carrying-latches of the cover are tripped.

Each set of latch-bars is prevented from latching any other cover but its own particular one by the operation of the guide-faces of the latch-bars. Thus when the cab is ascending it will be seen that the latch-bar is first depressed into its recess in the housing by the uppermost roller *a*² (which is on the platform) striking against its face *g*¹⁰, and it will remain depressed during the passage of all the covers (supposing there are a number) until the roller *a*² of the last cover passes the guide-face *g*¹⁰. At that moment the roller *a*² next above it just passes off the inclined shoulder *g*¹¹, and thus frees the latch-bar which, compelled by its spring, moves outwardly and receives the roller *a*² of the last cover in the recess, and, as before described, at the very same moment the cover is also released from the cab, and it will thus remain in the hatch-opening supported by the latch-bars at the four corners. Thus one cover after another, beginning from the bottom up, will be placed in a hatch-opening as the cab ascends and be firmly supported therein near the four corners by the four latches. Upon the cab going down again all the covers will be picked up again by the cab one after another in the following manner: Supposing there was no cover left under the cab, then the rollers *a*² on the platform of the cab in going down will strike against the shoulder *g*¹¹ of the latch-bars, depress the same, and thus free the cover from engagement with the notch of the latch-bar. At the same moment it will automatically reengage with its proper carrying-latches on the cab. This cover in succession will operate the set of

latch-bars next below, thereby freeing another cover from its latch-bars and permitting it to reengage with its carrying-latches, and so on as far as the cab is descending. I make the recess g^8 in the latch-bars of greater height than required for the rollers a^3 , thus allowing the covers a slight vertical play, which is made necessary to prevent any failure of the parts to coöperate together in the 10 manner described, and to still further insure safety I do not release the cover from its carrying-latches until it is fairly caught within the recess of the latch-bar, each cover being thus for the instant both held by its carrying-latches and by its supporting-latches both in the ascending and descending of the cab, and to prevent any creation of noise in the piling up of the covers beneath the platform when the cab descends I provide the covers at the 20 corners with rubber or spring buffers a^3 , which provide a slight vertical play of the cover and deadens the noise.

As regards the operation of the upper set of hatch-covers it is obvious that by supporting them on top of the cab, one on top of the other, the carrying-latches may be entirely dispensed with, and for supporting the hatch-covers of the upper set in the hatch-opening of the floors the same supporting-latches are 25 used as for the lower set, only they are placed in the reverse position, as they have to lock the covers when the cab descends and unlock when the cab ascends. These supporting-latches G' for the upper set I preferably place 30 beside the supporting-latches G and unite them into a common frame, and in connection therewith I provide the cover of the upper set with the rollers a^4 , which have precisely the same function as the rollers a^3 and 35 are placed at the corner-brackets and similarly arranged in vertical line with each other and with the latches G' . The device for operating the upper set of hatch-covers in construction and operation is thus the same as 40 those for the lower set, with the exception that the carrying-latches and operating devices therefor are dispensed with.

In my construction the dead-weight of the cab is only increased by the weight of one 45 half of the covers, as the other half will always remain supported in the hatch-openings no matter what the position of the cab, and the fluctuations which occur in such weight during the operation by taking off one cover 50 from one set and adding another of the other set will make no perceptible disturbance in the running of the elevator, and all noise created by the operation of the parts is obviated.

55 I am aware that it has been attempted heretofore to have the cab provided with devices for carrying the covers and locking them in the hatch-openings in the hatchway; but this has been found objectionable in elevators having any degree of speed for reasons which need 60 not be explained here, and my device is es-

pecially calculated to operate under all conditions of speed.

As it is important in the operation of the device that the covers move in prescribed positions, which may be affected by the slight oscillations which ordinarily take place in the movement of the cab, I preferably provide within the hatch-opening the inclined guide-rails H , which I preferably unite with or support inside the frame of the supporting-latches G G' , as shown in Figs. 5, 6, and 7, and in connection therewith I place on the sides of the cab-platform suitable antifriction-rollers I , adapted to engage upon these guide-rails and thereby prevent oscillation of the cab in passing through the hatch-openings.

It is also obvious that those of the rollers a^2 a^4 which are secured to the cab itself may be entirely dispensed with by using an extra 85 cover below and above the cab.

What I claim as my invention is—

1. The combination with the elevator-car of a hatch-cover adapted to be supported in a hatch-opening of the elevator-shaft, carrying-latches depending from the platform of the cab and shouldered latch-bars loosely carried by the latches adapted to automatically engage with and support the cover beneath the platform, substantially as described. 90

2. The combination with the elevator-car of a hatch-cover and carrying-latches depending from the platform of the car and having shouldered latch-bars adapted to automatically engage with and support the cover and provided with tripping-levers adapted to disengage said latch-bars from the cover, substantially as described. 100

3. The combination with the elevator-cab, of a hatch-cover, carrying-latches depending from the platform of the cab and having shouldered latch-bars adapted to automatically engage with and support the cover, a trip-lever on each latch having an automatically-projecting arm, fixed stops in the path 105 of the tripping-levers and supporting-latches in the hatch-opening having latch-bars adapted to automatically engage with and support the cover in the hatch-opening, substantially as described. 115

4. The combination with the elevator-cab, of a hatch-cover, carrying-latches depending from the platform of the cab and having latch-bars adapted to automatically engage with and support the cover beneath the platform, supporting-latches in the hatch-openings having latch-bars for supporting the cover in the hatch-opening and projections or rollers on the sides of the platform in line with and coöperating with said supporting-latches 120 to disengage their latch-bars from the cover by the downward movement of the cab, substantially as described. 125

5. The combination with the elevator-cab, of a hatch-cover, carrying-latches adapted to automatically engage with and support the same below the platform of the cab, and trip-

levers to disengage the same from said carrying-latches, stops in the hatch-openings to operate said trip-levers, supporting-latches in the hatch-opening adapted to automatically engage with and support the cover in the hatch-opening and projections or rollers on the cab, coöperating with said supporting-latches to disengage the same from the cover in the downward movement of the cab, substantially as described.

6. The combination with the elevator-cab, of a hatch-cover such as D, provided with the supporting-rollers d and a^2 , the carrying-latches E adapted to automatically engage with the rollers d of said cover to support the same and provided with the trip-levers e^6 to disengage said latch from the cover, the stops F in the hatch-openings adapted to trip the carrying-latches, the supporting-latches G in the hatch-openings provided with the recessed latch-bars adapted to automatically engage with the rollers a^2 to support the cover on the hatch-opening and the rollers a^2 on the platform of the cab adapted to disengage the cover from the supporting-latches in the downward movement of the cab, substantially as described.

7. The combination in an elevator, of a hatch-cover and supporting-latches therefor in the openings of the hatchway, each supporting-latch being provided with a latch-bar having a recess g^8 adapted to automatically engage with and support the hatch-cover upon one of the shoulders of the recess g^8 , substantially as described.

8. The combination in an elevator, of a supporting-latch for hatch-cover composed of the frame g , the jointed latch-bars g^2 g^3 , the recess g^8 being formed at the joint of the latch-bar and the latch-bars having the guide-faces g^{10} g^9 , the latter having the shoulder g^{11} , substantially as described.

9. The combination with the elevator-cab and two sets of hatch-covers, one adapted to be carried beneath the platform of the cab and the other on top thereof, of rollers or projections on each cover at or near the corners thereof and with the corresponding rollers or projections on each set of covers in the same

vertical line but different in the two sets and 50 a set of supporting-latches in each hatchway for each set of covers, the supporting-latches of one set being in line with the corresponding rollers on one set of hatch-covers and those of the other set in line with the corresponding 55 rollers or projections of the other set of hatch-covers, the hatch-openings having recessed latch-bars adapted to automatically engage with and support the hatch-covers, substantially as described.

10. The combination with the elevator-cab, of carrying-latches dependent from the platform of the cab, a lower set of hatch-covers with which said carrying-latches are adapted to automatically engage to support said covers 60 below the cab, means for tripping the carrying-latches in the hatch-openings, supporting-latches in the hatch-openings adapted to automatically engage with and support the lower set of covers in the hatch-openings, an upper 65 independent set of hatch-covers supported on top of the cab, supporting-latches therefor adapted to automatically engage with and support the covers of the upper set in the hatch-openings independently of the lower set 70 and rollers or projections on the hatch-covers and the cab adapted to coöperate with the supporting-latches to operate the same in the movement of the cab, substantially as described.

11. The combination with an elevator-car, of a hatch-cover, the cover carrying means on the car comprising a series of frames, each frame having a pivoted latch-bar thereon, and means acting automatically for tripping the 85 latch-bars, substantially as described.

12. The combination with an elevator-car, of a series of hatch-covers, and a series of carrying-frames extending from the car, each frame being provided with a series of automatically-operating latch-bars, substantially 90 as described.

In testimony whereof I affix my signature in presence of two witnesses.

HORACE B. MURDOCK.
